W. E. FICKLEN.
EDGE PROTECTOR FOR ARTIFICIAL STONE.
APPLICATION FILED AUG. 16, 1916.
1,257,686.

Patented Feb. 26, 1918

Inventor
William E. Ficklen,
By his Attorney
Frank, Wright & Snell.

UNITED STATES PATENT OFFICE.

WILLIAM E. FICKLEN, OF COLLEGE POINT, NEW YORK, ASSIGNOR TO CLIP BAR MANUFACTURING COMPANY, OF PHILADELPHIA, PENNSYLVANIA, A CORPORATION OF PENNSYLVANIA.

EDGE-PROTECTOR FOR ARTIFICIAL STONE.

1,257,686.

Specification of Letters Patent. Patented Feb. 26, 1918.

Original application filed October 26, 1912, Serial No. 727,919. Renewed January 15, 1916, Serial No. 72,369. Divided and this application filed August 16, 1916. Serial No. 115,149.

To all whom it may concern:

Be it known that I, WILLIAM E. FICKLEN, of College Point, in the county of Queens, and in the State of New York, have invented 5 a certain new and useful Improvement in Edge-Protectors for Artificial Stone, and do hereby declare that the following is a full, clear, and exact description thereof.

My invention relates to metal nosings, or 10 edgings, for artificial stone and is a division of my copending application filed October 26, 1912, Serial No. 727,919, renewed January 15, 1916, Serial No. 72,369, now Patent No. 1,201,952, granted October 17, 1916. 15 More particularly the invention is adapted as an edging for curbs, gutters and other structures, the edges of which are curved or rounded longitudinally. In curbs and gutters, such curves occur at street corners, and 20 may occur at other points, if the streets or roads are not straight. Metal edge-protectors of the general character of the present invention are positioned in the concrete or other material forming the artificial stones 25 or blocks, before the material has set; and, according to the shape of the metal, are more or less securely anchored in the material by the setting or hardening of the latter. For many uses, as for instance when 30 used as a curb or gutter edge, the metal must be of substantial size and strength; and, to have the requisite rigidity and depth of anchorage, is usually provided with a web or rib which lies in a plane transverse to the 35 direction in which the edge extends.

A favorite type of edge protectors has the general shape of a T iron, the cross member of which is the wearing member, and the upright of which is the anchoring member. 40 As shown in the accompanying drawings, the wearing member is of heavy "bull nose" conformation. This form of protector, although admirable so far as its wearing qualities are concerned, is difficult to bend to the 45 shape of corners and other curves. In many instances it is impossible to bend the protector, cold, and at the place of use; and great delay and expense are involved in ordering especially shaped sections from the 50 shops. Obviously, special shapes cannot be kept in stock in any sufficient amount to meet demands. The difficulty in bending is obviously due to the position of the rigid central web, and to the lines on which it

must be bent in following the street corners 55 and curves. Some forms of T bars are provided with large spacious openings or cuts at considerable intervals to serve as elements to interlock the concrete with the protector. Where such openings or cuts exist, the bar 60 can be bent, but the difficulty of bending the bar to the true curve is nevertheless increased, because the bar will always bend at the weakest point, and so bends out at the cuts or openings. A bar bent in this latter manner is not only humped and unsightly, but is weak at the curves, where, to receive the impact of heavy trucking and the like, it should be strongest.

The purpose of the present invention is 70 to render the anchoring web pliable so that it can be shaped to any curve, while cold, and at the place where it is to be used; without, however, involving a shortening of the web, or otherwise materially weakening the 75 web, or lessening the depth of anchorage, and also to anchor the web securely in the concrete. This purpose is effected in the present invention by perforating the web with numerous closely arranged small openings or by cuts of various kinds. In addition to the perforations, it is desirable to form anchoring tongues or forced out portions 80 on the bar. The perforations, of course, by reason of the concrete which enters the same, will in themselves, to a greater or less extent, assist in anchoring the bar; and, according to the nature of the 85 conglomerate, should be considered in this connection. The holes lying close together, 90 permit bending of the web, both laterally and vertically; so that, at the curves, the distal edges of the web may be crimped, and the web turned slightly from its position of perpendicularity to the wearing nose to allow for the difference in length of radius of the outer and inner portions of the bar at 95 such points.

An important feature of the invention concerns the manner in which the protector 100 and concrete are bound together. Heretofore, the anchoring of the bar has been effected either by projections from the bar, or by holes in the bar, spaced at considerable intervals apart. When such a bar is subjected to heavy blows, it will work loose 105 from the concrete between the points of anchorage, and presently will have a slight

play or spring, so that thereafter each blow on the bar will cause the bar to act as a wedge tending to split the concrete. In many instances the concrete will ultimately 5 split entirely away on one side of the bar. In the present invention however by reason of the large number of small anchoring points provided by the numerous perforations or cuts, or by reason of a part 9 forced 10 down from the web to form anchoring portions, there can be no starting point for any looseness of the bar. The bar and concrete are interwoven and interlocked at substantially all points of the bar; and destruction 15 of the curb in the manner above indicated is positively prevented.

The above and other features of the invention will more fully appear upon reference to the accompanying drawing, in which the 20 figure shows a strip or short piece of an edge protector embodying one form of the present invention.

Referring to the figure, the bar is shown of a general T shape, the wearing nose 1 of 25 which is of heavy "bull nose" conformation; and the web 2 of which tapers slightly to its distal edge 3. The web is corrugated to present a rough and uneven surface to the concrete to provide anchorage. At intervals along the web 2, the web is cut on longitudinal lines 8 and has portions 9 forced down from the same to provide openings 10 through which the concrete is interlocked with the bar when in place. The cuts 8 and 30 protrusions 10 are preferably closely arranged. While these cuts are shown as made on straight lines, it is obvious that the lines of severance may be curved, serrated, or otherwise shaped without departing from 35 the spirit of my invention. In addition to these cuts 8 and protrusions 10, the web 2 has several rows of perforations 6 formed by punching and bending small pieces 6' 40 out of the web. By reason of the perforations the web can be readily turned laterally out of its perpendicular position with respect to the nose 1, on the line of the top row, or of any other row, of holes 6; and can also be bent in a transverse direction on the 45 line of any vertical row of the holes 6. In certain instances, either the cuts 8 alone, or the holes 6 alone, will be sufficient for the 50 purposes of this invention. In other instances, both may be desirable. Obviously, 55 when the bar is placed in the unset concrete, the latter will enter the holes 6; and, because of the number of the latter, and also because of the projections 6', the concrete, when it has set, will be so interlocked with 60 the bar as effectively to assist the tongues 4 in anchoring the bar to the concrete 65 throughout the length of the same. The openings 10 also serve, either alone or with holes 6, as a secure locking means. It is evident that any shocks are transmitted

through the web to the deep anchoring portion formed by openings 10. No finished metal is wasted in forming these openings 10, which can be made economically and without materially lessening the cross section of the web at any point. 70

The invention may take various other forms, within scope of the principles above indicated.

What I claim is:

1. An edge protector for concrete curbs, gutters and the like, having a wearing member, and a web, the web having several vertical and horizontal rows of small holes therein and anchoring projections extending 80 therefrom, and also having closely set, longitudinal cuts adjacent to the edge thereof, and having portions integral at both ends with the web expanded out of the web between said cuts and the edge of the web and 85 extending in the plane of the web.

2. An edge protector for concrete curbs, gutters and the like, having a wearing member, and a web, the web having a series of 90 small holes therein, and also having closely set, longitudinal cuts adjacent the edge thereof, and having portions integral at both ends with the web expanded out of the web between said cuts and the edge of the web and 95 extending in the plane of the web.

3. An edge protector for concrete curbs, gutters and the like, having a wearing member, and a web, and anchoring projections extending therefrom, and also having closely set, longitudinal cuts adjacent the 100 edge thereof, and having portions integral at both ends with the web expanded out of the web between said cuts and the edge of the web and extending in the plane of the web.

4. An edge protector for concrete curbs, gutters and the like, having a wearing member, and a web, the web having a series of small holes therein and anchoring projections extending therefrom, and also having 110 closely set, longitudinal cuts adjacent the edge thereof, and having portions integral at both ends with the web expanded out of the web between said cuts and the edge of the web and 115 extending in the plane of the web.

5. An edge protector for concrete curbs, gutters, and the like, having a wearing member, and a corrugated web, the web having several vertical and horizontal rows of small holes therein, and also having closely set, longitudinal cuts adjacent the edge thereof, and having portions integral at both ends with the web expanded out of the web between said cuts and the edge of the web and 120 extending in the plane of the web.

6. An edge protector for concrete curbs, gutters, and the like, having a wearing member; and a corrugated web, and anchoring projections extending therefrom, and also 125

100

105

120

125

130

having closely set, longitudinal cuts adjacent the edge thereof, and having portions integral at both ends with the web expanded out of the web between said cuts and the 5 edge of the web and extending in the plane of the web.

7. An edge protector for concrete curbs, gutters, and the like, having a wearing member; and a corrugated web, the web having 10 several vertical and horizontal rows of small holes therein and anchoring projections extending therefrom, and also having closely set, longitudinal cuts adjacent the edge thereof, and having portions integral at 15 both ends with the web expanded out of the web between said cuts and the edge of the web and extending in the plane of the web.

8. An edge protector for concrete curbs, gutters, and the like, comprising a wearing 20 member, and a web having portions expanded out of the web in substantially the plane of the web, and a zone of small holes through the web between said expanded portions and the wearing member, and holes being closely 25 stepped both along and across said zone to present a screen-like structure for interweavement of the web with the concrete and to assure flexibility of the web.

9. An edge protector for concrete curbs, 30 gutters, and the like, comprising a wearing member, and a web connected to said wearing member and integral therewith having portions integral at both ends with the web and expanded out of the web in substantially 35 the plane of the web.

10. An edge protector for concrete curbs,

gutters, and the like, comprising a wearing member of sufficient face area to protect the said edge, and a web connected to said wearing member and integral therewith for supporting said wearing member and adapted to sustain impact forces delivered to said wearing member and having portions integral at both ends with the web and expanded out of the web in substantially the plane 40 of the web and adapted to interlock with the concrete and anchor the protector in position.

11. An edge protector for concrete curbs, gutters and the like comprising a wearing 50 member and a web connected to said wearing member, said member having a series of loops at that edge remote from said wearing member and extending with said member, said loops formed by stretching or expanding strips or portions separated from said main portion, to form said loops.

12. An edge protector for concrete curbs, gutters and the like, comprising a wearing 60 member of sufficient face area to protect the edge, and a web for supporting said wearing member and adapted to sustain impact forces delivered to said wearing member, and having a series of portions integral at both ends of the web and expanded out of 65 the web in substantially the plane of the web, forming deep anchoring portions, adapted to interlock with the concrete and anchor the structure in position.

In testimony that I claim the foregoing I 70 have hereunto set my hand.

WILLIAM E. FICKLEN.
